ABSTRACT OF THE DISCLOSURE

Azaboranes of the formula $MHNB_9H_{12}$ or
 $RR'R''NNB_9H_{12}$

where M is a cation and the R's are selected hydrocarbyl groups. The azaboranes are prepared by reacting an N-thionitrosodialkylamine with decaborane at $-25^\circ C$. to $100^\circ C$. in an inert solvent. The azaboranes are useful as blowing agents, in electrical resistors and as reducing agents.

This application is a continuation-in-part of my pending application Ser. No. 490,712, filed Sept. 27, 1965, now abandoned and my copending application Ser. No. 490,661, filed Sept. 27, 1965.

This invention relates to boron-containing compounds and processes for their preparation. More specifically, the invention relates to polyhedral polyboron compounds having a nitrogen atom in the polyboron nucleus.

The novel compounds of this invention, hereinafter called azaboranes, all contain the $-NB_9H_{12}$ nucleus in which the nitrogen is an integral part of the borane structure. More particularly, the novel compounds have the structural formulas

- (1) $MHNB_9H_{12}$ and
- (2) $RR'R''NNB_9H_{12}$

In Formula 1, the nucleus nitrogen is additionally bonded to the hydrogen, while in Formula 2, it is additionally bonded to the nitrogen of the $NR'R''$ group. The compounds of Formula 2 are N-(substituted-amino) derivatives of the compounds of Formula 1. R' and R'' are defined as alkyl groups of up to 12 carbon atoms each or together are alkylene of 2-12 carbon atoms. M and R represent one equivalent of a cation selected from alkali metals, alkaline earth metals, GG_3N^+ , G_4P^+ , G_3S^+ , G_4As^+ or G_4Sb^+ . In addition, R can be a straight chain alkyl group of 1-3 carbon atoms or an aralkyl group of 7-10 carbon atoms, and in these two instances, the compounds of Formula 2 can be considered to be an inner-salt or zwitterion.

G is defined as a monovalent hydrocarbyl group of up to 18 carbon atoms that is free of aliphatic carbon-to-carbon unsaturation, and G' is a monovalent hydrocarbyl group of up to 18 carbon atoms that is free of aliphatic carbon-to-carbon unsaturation and is bonded to N through an aliphatic carbon atom. Preferably, G and G' each contain up to 12 carbons. Any two G or G' groups in the same cation can also be joined (bonded) directly to each other or through an oxygen hetero atom, to form a divalent alkylene group or oxygen-interrupted (mono-oxa) alkylene group of 4-8 carbons. The term "free of aliphatic carbon-to-carbon unsaturation" means that the hydrocarbyl group contains no aliphatic ethylenic or acetylenic bonds, i.e., the only unsaturation that may be present is aromatic.

Examples of these cations include benzyltrimethylammonium, N,N-diethyl-2,5-dimethylpyrrolidinium, dodecyl-

2

trimethylammonium, cyclohexyltrimethylammonium, N-methyl-N-octadecylmorpholinium, tetrabenzylphosphonium, ethylpentamethylene-p-tolylphosphonium, benzyl-hexadecylidimethylphosphonium, isobutylethylmethylisopropylphosphonium, benzyltris(4-biphenyl)phosphonium, triphenylsulfonium, methyltetramethylenesulfonium, methyldiphenylsulfonium, cyclohexylidimethylsulfonium, tetramethylarsonium, 2-biphenyltrimethylarsonium, methyltri(p-tolyl)arsonium, tetraphenylstibonium, decyltriphenylstibonium, t-butylethyldimethylammonium, and the like.

Of the G- and G'-substituted cations above, the ammonium, phosphonium, and sulfonium are preferred because of availability. For the same reason, those containing only lower alkyl substituents (1-8 carbon atoms) are preferred.

The group G' can only be bonded to the nitrogen through an aliphatic carbon atom, i.e., G' cannot be aryl where the aryl group is bonded directly to the nitrogen.

Examples of alkyl and aralkyl R groups include $-CH_3$, $-C_2H_5$, $-C_3H_7$, $C_6H_5CH_2$, $p-CH_3C_6H_4CH_2$, $p-(CH_3)_2CHC_6H_4CH_2$, and the like.

The $-NB_9H_{12}$ nucleus of the compounds of this invention is believed to be, at least in part, a polyhedral fragment consisting of nine boron atoms and one nitrogen atom, with three hydrogen atoms in bridging positions or BH_2 groups, but the exact geometrical configuration is not known at this time.

The compounds of Formula 2 where R is M can be prepared from an N-thionitrosodialkylamine and decaborane(14) according to the equation

where R' and R'' are alkyl groups of up to 12 carbons each or together are an alkylene group of 2-12 carbons. The reaction is carried out at temperatures ranging from -25° to $100^\circ C$., preferably $0-25^\circ C$., in an inert solvent. Neither pressure nor time of reaction is critical. Atmospheric pressure is preferred for convenience, although subatmospheric or superatmospheric pressures may be employed. The solvent employed is preferably an ether, and most preferably a dialkyl ether of 2 to 10 carbons or a cyclic aliphatic hydrocarbon ether, such as dioxane, tetrahydrofuran, and the like. Aromatic hydrocarbon solvents, such as benzene or xylene, or ester solvents such as ethyl acetate can also be employed.

The ratio of reactants is not critical and can range from 1:10 or more to 10:1 or more, although preferably the ratio is usually about 2:1 $R'R''NN$ to $B_{10}H_{14}$.

Also produced in the reaction is the anion $B_{10}H_{11}S^-$. Both anions are contained in a solid mixture which forms during the reaction. Upon treating the solid with aqueous alkali-metal hydroxide (1-50 percent), e.g., NaOH, the alkali-metal salt of each anion is obtained in the aqueous layer. The aqueous solution is then treated with a solution of a compound containing a precipitating cation, e.g., tetramethylammonium chloride, whereupon the tetramethylammonium salts containing both anions precipitate.

The compounds containing the two different anions can be separated by taking advantage of their different solubilities in certain solvents. For example, upon treatment with hot ethanol, the $(CH_3)_4NB_{10}H_{11}S$ is precipitated while the $(CH_3)_4NR'R''NNB_9H_{12}$ dissolves. Upon removing the solvent, the tetramethylammonium salt of the compound of Formula 2 is isolated. Alternatively, the mixture of salts can be dissolved in a solvent such as acetone and the salts selectively precipitated by careful addition of a relatively poor solvent, such as ether, benzene or chloroform.

Once the tetramethylammonium salt is obtained, any of the other cations defined by M or R can replace the tetramethylammonium cation by well-known cation ex-

change procedures. Specific cation-exchange resins can be employed.

Once the salts, $M(R'R''NNB_9H_{12})$, are obtained, the cation can be replaced by alkyl or aralkyl groups (to complete the definition of R in Formula 2) through alkylation of the salts with an alkylating agent $R_g'''X$ wherein R''' is straight chain alkyl of 1-3 carbon atoms or aralkyl of 7-10 carbon atoms, and X is a leaving group of valence g. The term "leaving group" is used as described in Gould, "Mechanism and Structure in Organic Chemistry," Holt-Dryden, 1959, p. 261. Preferably, X is chloride, bromide, iodide, sulfate, or a C_1-C_7 hydrocarbonsulfonate free of aliphatic unsaturation, i.e., any unsaturation present is aromatic. Thus, examples of $R_g'''X$ include dimethyl sulfate, methyl iodide, benzyl chloride, methyl p-toluenesulfonate, ethyl methanesulfonate, and the like. This alkylation process is generally carried out at mole ratios of $R_g'''X$ to $R'R''NNB_9H_{12}^-$ of at least 1:1 and can be as high as 200:1. Temperatures will be between -25° and 100° C., but preferably will be between $25-35^\circ$ C. Neither pressure nor time is critical. Atmospheric pressure is usually employed for convenience, while the time can range from a few seconds to 1 or more days. A convenient time of reaction at 35° C. is about one hour.

The alkylation is carried out in an inert solvent. Suitable solvents include aliphatic or aromatic hydrocarbon ethers such as 1,2-dimethoxyethane, di(2-methoxyethyl)ether, diphenyl ether, tetrahydrofuran, dioxane and the like; aliphatic or aromatic nitriles such as propionitrile, benzonitrile, and the like; esters such as propyl acetate, methyl benzoate, butyl propionate and the like; aliphatic alcohols such as cyclohexanol, butanol and the like; or ketones, as for example, acetone or acetophenone. Thus it is seen that the particular solvent employed is important only in facilitating isolation of the products.

Compounds of Formula 1 are obtained by treating a compound of Formula 2 with a reducing agent in a neutral or alkaline medium. Reducing agents employed include sodium, lithium, potassium or calcium metals, basic zinc dust or any basic hydrosulfite solution, such as an alkali metal hydrosulfite. With metallic reducing agents that react rapidly with water, a non-aqueous medium is employed as for example, ethers, such as tetrahydrofuran 1,2-dimethoxyethane, or dioxane. With alkali metals and alkaline earth metals, the temperature is critical and must be between about 50° and 75° C.; otherwise temperature is not critical.

The products of the invention are generally colorless, crystalline solids that are stable to air and to water at normal-to-moderate temperatures. Salts containing the $R'R''NNB_9H_{12}^-$ anion usually melt above about 150° C., and salts containing the $NHB_9H_{12}^-$ anion usually melt above about 250° C. The hydrocarbylated, zwitterionic compounds $R'R''NNB_9H_{12}$ are insoluble in water but soluble in polar organic solvents, e.g., alcohol, acetone, and acetonitrile.

The products and processes of this invention are illustrated in further detail in the following examples.

EXAMPLE I

To a stirred solution of 18.5 g. of decaborane(14) in 450 ml. of ether was added dropwise over 30 minutes at room temperature 200 ml. of 0.7 M N-thionitrosodimethylamine solution in ether. The mixture was stirred for an additional 30 minutes after addition was complete. The supernatant liquid was decanted from the gum which had separated, and the gum was washed with ether. The gum was extracted with about 200 ml. of 10% aqueous sodium hydroxide solution. The extract was filtered, and the filtrate was treated with excess tetramethylammonium chloride. The resulting precipitate was collected by filtration and then extracted with warm ethanol, and the mixture was filtered. The filtered ethanol extract was concentrated under reduced pressure, and then treated

with about twice its volume of 1:1 benzene-cyclohexane to give 4.9 g. of $(CH_3)_4N(CH_3)_2NNB_9H_{12}$ which was collected by filtration. The product was purified by recrystallization from ethanol-cyclohexane (ca. 2:1) followed by recrystallization from a small volume of ethanol to give crystals with M.P. $197-198^\circ$ (bubbling).

Analysis.—Calcd. for $C_6H_{30}B_9N_3$: C, 29.9; H, 12.5; B, 40.3; N, 17.4. Found: C, 30.1; H, 12.1; B, 40.4; N, 17.4.

The product shows ultraviolet absorption in acetonitrile solution at $285\text{ m}\mu$ ($\epsilon 1510$) with a shoulder at $225\text{ m}\mu$ ($\epsilon 6100$). The H^1 nuclear magnetic resonance spectrum of the product in acetonitrile- d_3 at 60 mc. shows three peaks at 7.1τ ($(CH_3)_4N^+$, relative intensity 4), 7.86τ ($N-CH_3$, relative intensity .74), and 7.97τ ($N-CH_3$, relative intensity 1.1) suggesting the presence of two isomers.

Platinum-catalyzed acid hydrolyses of a similar sample gave 1750.3 and 1753.1 cc. of hydrogen per gram of sample, consistent with the equation

which requires 1762 cc. of hydrogen per gram of

The use of other N-thionitroso secondary amines in place of N-thionitrosodimethylamine in Example I gives products of the invention containing other hydrocarbyl groups as values of R' and R''. For example, N-thionitrosodibutylamine gives $(CH_3)_4N(C_4H_9)_2NNB_9H_{12}$, N-thionitrosopyrrolidine gives $(CH_3)_4N(CH_2)_4NNB_9H_{12}$, N-thionitrosodecamethyleneimine gives

and N-thionitrosodidecylamine gives

If salts containing other precipitating cations are substituted for tetramethylammonium chloride in essentially the procedure of Example I, the corresponding salts containing these cations and the $R'R''NNB_9H_{12}^-$ anion can be obtained. For example, tetraphenylphosphonium iodide gives $(C_{10}H_7)_4P(CH_3)_2NNB_9H_{12}$, methyltetramethylenesulfonium bromide gives

tetraphenylarsonium chloride produces

and tetramethylstibonium chloride gives

Alternatively, a solution of $(CH_3)_4N(CH_3)_2NNB_9H_{12}$ can be passed through a column packed with a sodium cation-exchange resin, and the solution of

thus obtained can be treated with the salts containing the precipitating cations mentioned in the preceding paragraph, whereupon the salts containing these cations and the $(CH_3)_2NNB_9H_{12}^-$ anion precipitate.

EXAMPLE II

A solution of 1.5 g. of $(CH_3)_4N(CH_3)_2NNB_9H_{12}$ and 5 ml. of methyl iodide in 35 ml. of acetonitrile was refluxed for 45 minutes. The mixture was evaporated under reduced pressure, and the residue was suspended in water, and filtered. The filter cake was washed with water to give 1.17 g. of $(CH_3)_3NNB_9H_{12}$ as a pale yellow solid. The product was purified by recrystallization from acetonitrile-ethanol to give colorless crystals, which decomposed quite suddenly at 176.5° with formation of copious amounts of gas.

Analysis.—Calcd. for $C_3H_{21}B_9N_2$: C, 19.7; H, 11.6; B, 53.3; N, 15.4. Found: C, 18.6, 20.6; H, 11.4, 11.3; B, 53.3, 52.8; N, 16.8

The ultraviolet spectrum of the product in acetonitrile shows absorption at 223 $m\mu$ (ϵ 100). The H^1 n.m.r. spectrum of the product in acetonitrile- d_3 shows a single peak at 7.02 τ ($-N(CH_3)_3$). The infrared spectrum of the product shows absorption characteristics of the $-N(CH_3)_3$ group at 1481 cm^{-1} . There is no absorption attributable to N-H.

Platinum-catalyzed acid hydrolysis of the product gave 2350.3 cc. of hydrogen per gram of compound, consistent with the equation

which requires 2330 cc. of hydrogen per gram of $(CH_3)_3NNB_9H_{12}$.

By substituting other hydrocarbylating agents for the methyl iodide of Example II, other products of the invention can be obtained. For example, propyl p-toluenesulfonate gives $C_3H_7(CH_3)_2NNB_9H_{12}$, benzyl chloride gives $C_6H_5CH_2(CH_3)_2NNB_9H_{12}$, and 3-phenylpropyl bromide gives $C_6H_5CH_2CH_2CH_2(CH_3)_2NNB_9H_{12}$.

EXAMPLE III

A mixture of 3 g. of $(CH_3)_4N(CH_3)_2NNB_9H_{12}$, 100 ml. of anhydrous tetrahydrofuran, and about 10 ml. of a 50% dispersion of metallic sodium in mineral oil was stirred at reflux for 20 hours under a nitrogen atmosphere. The mixture was cooled and treated with ethanol to destroy unreacted sodium, and then evaporated to dryness under reduced pressure. The residue was treated with water and pentane, and the layers were separated. The aqueous layer was treated with tetramethylammonium chloride, and the resulting precipitate was collected by filtration to give 1.89 of colorless solid. Crystallization from ethanol gave .24 g. of $(CH_3)_4NNH_2B_9H_{12}$ as colorless plates, M.P. $>300^\circ$.

Analysis.—Calcd. for $C_4H_{25}B_9N_2$: C, 24.2; H, 12.7; B, 49.0; N, 14.1. Found: C, 24.5; H, 12.4; B, 50.1; N, 14.6, 13.5, 13.7.

Platinum-catalyzed acid hydrolyses of the product gave 2084 and 2106 cc. of H_2 per gram of compound in accord with the equation

which requires 2140 cc. of H_2 per gram.

The infrared absorption spectrum of the product shows absorption at 3390 (N-H str.) and 2580–2350 cm^{-1} (complex, B-H str.). The absence of absorption attributable to NH deformation confirms the presence of an N-H group rather than an NH₂ group.

The 60 mc. n.m.r. spectrum of $(CH_3)_4NNH_2B_9H_{12}$ in acetonitrile- d_3 shows two peaks at τ 7.11 [$(CH_3)_4N$] and τ 7.91 (sl. broad, N-H) in the ratio 12:1 consistent with the proposed structure.

By substituting other ammonium, phosphonium, sulfonium or stibonium salts for the tetramethylammonium chloride, such cation-containing salts can be precipitated. Thus, the tetraphenylphosphonium, methyltetramethylene-sulfonium, tetraphenylarsonium and tetramethylstibonium salts can be obtained as described in Example I.

EXAMPLE IV

A solution of 0.60 g. of $(CH_3)_4NNH_2B_9H_{12}$ in about 100 ml. of 1:1 aqueous acetonitrile was passed through a column packed with a sodium cation-exchange resin. The effluent solution of $NaNNH_2B_9H_{12}$ was concentrated under reduced pressure to about 25 ml., and excess solid cesium sulfate was added. The solid that precipitated was collected by filtration, washed, and dried, to give 0.63 g. of $CsNNH_2B_9H_{12}$. Part of the product was further purified

by recrystallization from ethyl alcohol/benzene/cyclohexane.

Analysis.—Calcd. for $H_{13}B_9CsN$: H, 5.09; N, 5.45. Found: H, 5.40; N, 5.37.

The ultraviolet absorption spectrum of an aqueous solution of the product had an absorption of 218 $m\mu$ (ϵ 8570).

The sodium-ion-exchange resin was made from a commercial, sulfonated styrene copolymer cation-exchange resin ("Rexyn" 101 (H)) by passing aqueous sodium chloride through a column filled with the resin until the effluent was no longer acidic and then washing the resin free of chloride ion with water.

Cation-exchange resins containing other alkali metals or alkaline earth metals in place of sodium can be prepared in the same manner. Thus, other cations defined in Formulas 1 and 2 can be obtained such as $LiNNB_9H_{12}$, $KNNB_9H_{12}$, $Mg(HNB_9H_{12})_2$, $Ca(HNB_9H_{12})_2$,

$Ca(R'R''NNB_9H_{12})_2$, and the like.

The R'_2NNS reactant can be prepared by reacting a 1, 1-dialkylhydrazine, e.g., 1, 1-dimethylhydrazine with powdered sulfur at temperatures of 0° to 50° C. in an inert medium such as ether. The R'_2NNS can then be isolated by ordinary methods, e.g., distillation or recrystallization. This procedure is described in copending application Ser. No. 413,989, filed Dec. 8, 1964, in the name of W. J. Middleton, now U.S. 3,344,135, and assigned to the assignee of record herein.

The compounds of this invention can be employed as blowing agents in the production of polymeric foams. For example, a sample of "Elvax 250" ethylene-vinyl acetate copolymer was softened by heating, and a small portion of $(CH_3)_3NNB_9H_{12}$ was blended in. The resulting sample was then heated at 210°, and a foam was produced. Similar results were obtained with ethylene-carbon monoxide copolymer, tetra-fluoroethylene-isobutylene copolymer, and "Nordel" ethylene-propylene copolymer.

The compounds of the invention are also useful in the preparation of electrical resistors. A cotton string can be impregnated with a nearly saturated solution of a compound of the invention, in a volatile solvent such as acetonitrile. When the string is removed, dried and burned, a coherent ash is left which resembles the original string in size and shape. This ash is sufficiently coherent to permit embedding in paraffin for use as an electrical resistor. Resistors of up to 4200 ohms/mm. have been prepared in this fashion.

The novel compounds can be employed as reducing agents in preparing printed electrical circuitry. A circuit can be traced on paper using a solution of acetonitrile and one of the compounds of this invention. After evaporating the solvent, the tracings can be sprayed with an aqueous solution of palladium chloride. After rinsing, a metallic tracing of reduced palladium is left.

The foregoing detailed description has been given for clearness of understanding only and no unnecessary limitations are to be understood therefrom. The invention is not limited to the exact details shown and described, for obvious modifications will occur to those skilled in the art.

The embodiments of the invention in which an exclusive property or privilege is claimed are defined as follows:

1. A compound selected from the group consisting of $MNNB_9H_{12}$ and $RR'R''NNB_9H_{12}$ wherein

R' and R'' are selected from the class consisting of, individually, alkyl of up to 12 carbon atoms, and taken together, alkylene of 2 to 12 carbon atoms; M is one equivalent of a cation selected from the class consisting of alkali metal, alkaline earth metal, GG_3N^+ , G_2P^+ , G_3S^+ , G_4As^+ and G_4Sb^+ wherein G is hydrocarbyl of up to 18 carbon atoms that is free of aliphatic carbon-to-carbon unsaturation G' is hydrocarbyl of up to 18 carbon atoms that is free of aliphatic carbon-to-carbon unsaturation and is bonded

to N through aliphatic carbon, and G and G' can be joined to form a divalent group of 4-8 carbon atoms selected from the class consisting of alkylene and mono-oxaalkylene; and

R is selected from the class consisting of M, straight-chain alkyl of 1-3 carbon atoms and aralkyl of 7-10 carbon atoms.

2. The compound of claim 1 having the formula $MH_2N\text{NB}_9\text{H}_{12}$ wherein M is defined as in claim 1.

3. The compound of claim 1 having the formula $RR'\text{R}''\text{NNB}_9\text{H}_{12}$ wherein R, R' and R'' are defined as in claim 1.

4. The compound of claim 3 having the formula $R(\text{CH}_3)_2\text{NNB}_9\text{H}_{12}$ wherein R is defined as in claim 3.

5. The compound of claim 1 having the formula $(\text{CH}_3)_4\text{N}(\text{CH}_3)_2\text{NNB}_9\text{H}_{12}$.

6. The compound of claim 1 having the formula $(\text{CH}_3)_3\text{NNB}_9\text{H}_{12}$.

7. The compound of claim 1 having the formula $(\text{CH}_3)_4\text{NNHB}_9\text{H}_{12}$.

5

20

8. A process for preparing a salt of $\text{B}_{10}\text{H}_{11}\text{S}^-$ and a salt of $\text{R}_2\text{NNB}_9\text{H}_{12}^-$ wherein each R is alkyl of up to 12 carbon atoms and both R's together are alkylene of 2-12 carbon atoms, which comprises reacting R_2NNS with $\text{B}_{10}\text{H}_{14}$ at a temperature of from -25° to 100° C. in an inert ether, hydrocarbon or ester solvent.
